UNITED STATES PATENT OFFICE.

ABNER JUDSON McGEHEE, OF JACKSON, TENNESSEE.

FURNACE.

1,319,403.

Specification of Letters Patent.

Patented Oct. 21, 1919.

Application filed July 5, 1918. Serial No. 243,405.

To all whom it may concern:

Be it known that I, ABNER J. McGEHEE, a citizen of the United States, and a resident of Jackson, in the county of Madison and State of Tennessee, have invented certain new and useful Improvements in Furnaces; and I do hereby declare the following to be a full, clear, and exact description of the invention, such as will enable others skilled in the art to which it appertains to make and use the same.

This invention relates to improvements in furnaces and more particularly to a system for returning smoke and gases to the fire chamber,—one object of the invention being to provide simple and efficient means to effect economy in the use of fuel; to insure efficient combustion of returning gases mixed with air; to provide a construction in which fresh air will be preheated by heat supplied by the furnace before said air is mixed with the gaseous products of combustion from the furnace, and to insure proper and efficient circulation of the mixed air and gases.

With these and other objects in view, the invention consists in certain novel features of construction and combinations of parts as hereinafter set forth and pointed out in the claims.

In the accompanying drawings; Figure 1 is a view partly in section showing an embodiment of my invention, and Figs. 2 and 3 are views of modifications.

1, 2 represent two steam boiler furnaces constituting a battery, but it will be understood that my improvements are applicable to a battery comprising a greater number of furnaces.

A flue 3 is located horizontally over the plurality of furnaces and communicates with the smoke box of each of them,—one end of said flue being closed and the other end communicating with a stack 4, which latter may be located entirely outside of the furnace house, and dampers 4^a are located where said flue communicates with the smoke boxes of the furnaces.

The horizontal flue is divided by a partition 5 into chambers 6, 7,—the lower of which communicates with the smoke boxes of the furnace. The upper flue chamber 7 constitutes a mixing chamber and its end near the stack is adapted to be closed by a damper 8. The lower chamber 6 is adapted to communicate with the mixing chamber 7 through openings 9, 10 (of appreciably less

width than that of the partition) controlled by dampers 11, 12.

A return pipe 11^a is connected with the mixing chamber near its forward end (which is normally closed by the damper 8) and said pipe 11^a, after extending rearwardly and downwardly, communicates with the two furnaces under the grates thereof,—said return pipe being made with two branches 11^b, 11^c for this purpose. Each branch of the return pipe may be provided with a damper 17 and lateral pipes 18 project from the respective branches of the return pipe and are provided with nozzles 19 which enter the fire chamber,—said nozzles being adapted to discharge rearwardly and prevent the flame from playing constantly against any one part of the boilers.

A fresh air pipe 12^a passes transversely through the flue chamber 6 and communicates with the mixing chamber 7, in such manner that the draft of products of combustion passing through said chamber will tend to draw air into said chamber.

The fresh air pipe extends downwardly in close proximity to one of the furnaces and its boiler so that the air passing through said pipe will be preheated before it enters the mixing chamber. A damper 13 is located in the air pipe and in proximity to this damper, a fan 14 is adapted to force the air into the air pipe, said damper being so located that it may be operated to control the force of air forced into the pipe by the fan.

It will be seen that with my improvements, the air will enter the mixing chamber in a preheated condition and it will be kept hot while in said chamber, and the hot air mixed with the products of combustion from the furnace will be caused to flow through the return pipe to the fire boxes of the furnaces, where ready and efficient combustion of the mixed hot air and gases will be caused.

When the furnaces are first fired, the damper 8 may be opened to increase the draft through the stack and when only one of the furnaces is fired at a time, one of the dampers 11 or 12 and the damper 4^a of the idle furnace may be closed.

In the construction shown in Fig. 2, the mixing chamber 7 is formed within the smoke flue 3 by means of a pipe or tube 15 located centrally within the latter,—the portion of said flue 3 surrounding the tube

15 forming the flue chamber 6,—and the outer end of said tube near the stack is provided with a damper 16.

In the form of the invention shown in Fig. 3, the mixing chamber is formed by a tubular extension 20 disposed upon and at right angles to the flue 3,—said tubular extension communicating at its lower end with the flue 3 where the entrance of products of combustion is controlled by a damper 21. The upper end of the tube 20 is closed and the return pipe 11^a is connected with said tube near its closed upper end. An air inlet pipe 22 communicates with the tube 20 near the lower end of the latter and is located near the smoke flue and the adjacent boiler and is controlled by a damper 23. A fan 24 is provided to force air through the fresh air pipe 22.

20 Other changes might be made in the details of construction of my invention without departing from the spirit thereof or limiting its scope and hence I do not wish to restrict myself to the precise details herein set forth.

Having fully described my invention what I claim as new and desire to secure by Letters Patent, is:—

1. The combination with a furnace and its stack, of a horizontal flue located over the furnace and communicating with the same and with the stack, a mixing chamber associated and communicating with said horizontal flue, a damper for controlling such communication, an air inlet for the mixing chamber located to supply air heated by the furnace to the mixing chamber, and a return pipe communicating with the mixing chamber and with the furnace.

2. The combination with a plurality of furnaces and a stack, of a horizontal smoke flue located over said furnaces and communicating therewith and with the stack, a mixing chamber located within said horizontal flue and adapted to communicate therewith and with the stack, dampers for con-

trolling such communication, an air inlet located to admit heated air to the mixing chamber, a return pipe connected with said mixing chamber and with the furnaces, and means for forcing a draft through said mixing chamber and return pipe.

3. The combination with a battery of furnaces and a stack, of a horizontal smoke flue located over the furnaces and communicating therewith and with the stack, a mixing chamber within said flue and adapted to communicate therewith and with the stack, dampers for controlling such communication, an air pipe entering the horizontal flue and communicating with the mixing chamber therein, said pipe being located in position to be heated by furnace heat, a return pipe communicating with the mixing chamber and with the furnaces, and a fan located to create a draft through the air pipe, mixing chamber and return pipe.

4. The combination with a plurality of furnaces having smoke boxes, and a stack, of a horizontal flue located over the furnaces, a partition dividing said flue into two chambers, one of which communicates with the smoke boxes of the furnaces, and the other of said chambers constituting a mixing chamber adapted to communicate with the first-mentioned chamber and with the stack, dampers for controlling such communication, a return flue communicating with the end portion of the mixing chamber near the stack and with the furnaces, an air pipe communicating with the other end of the mixing chamber in position to admit air heated by the furnace, and means for forcing a draft through the mixing chamber and return pipe.

In testimony whereof, I have signed this specification in the presence of two subscribing witnesses.

ABNER JUDSON McGEEHEE.
